UNITED STATES PATENT OFFICE.

MAXAMILIAN JAEGER, OF NEW YORK, N. Y.

MATCH-HOLDER.

No. 839,766.

Specification of Letters Patent.

Patented Dec. 25, 1906.

Application filed January 22, 1906. Serial No. 297,189.

To all whom it may concern:

Be it known that I, MAXAMILIAN JAEGER, a citizen of the United States, and a resident of the city of New York, borough of Brooklyn, in the county of Kings and State of New York, have invented a new and Improved Match-Holder, of which the following is a full, clear, and exact description.

This invention relates to improvements in match-holders, the object being to provide a device of this character that may be attached to a wall or similar support and adapted to hold a full box of matches and so constructed that the matches will automatically feed downward to be removed one at a time, thus preventing waste of matches and obviating danger from fire by matches falling on the floor and igniting by a person's shoes, as sometimes happens.

20 I will describe a match-holder embodying my invention and then point out the novel features in the appended claim.

Reference is to be had to the accompanying drawings, forming a part of this specification, in which similar characters of reference indicate corresponding parts in both figures.

Figure 1 is a perspective view of a match-holder embodying my invention, and Fig. 2 is a sectional elevation thereof.

30 The match-holder consists of a box 1, of any suitable material—as, for instance, metal—the said box having an opening at its top provided with a cover, here shown as having hinged connection with the box; but it may be otherwise applied without departing from the spirit of my invention.

The back wall of the box near the top is provided with an opening 3 for receiving a nail or the like, and a similar opening 4 is formed in a downward extension 5 of said back wall, and this extension is provided with a roughened or abrading surface 6, on which the matches may be scratched.

40 At the lower portion of the box is a tray 7 for receiving matches, this tray being provided at its center with a notch 8, so that a person may conveniently grasp a match with his thumb and forefinger.

The front wall 9 at the bottom above the 50 tray is inclined downward and rearward and

is provided at the center with an opening 10, so that matches may be readily reached for agitating the same should the matches become clogged or stuck in the box.

At the sides of the opening 10 are downwardly and outwardly curved members 11, which serve as guides to direct matches into the tray and hold the same straight across the tray. The bottom rear wall 12 is inclined downward and forward, so that the 60 matches will slide down the same underneath the guide members 10. The front of the tray at the bottom has a trough-shaped portion 13 adapted to receive a single match which is to be removed.

65 A match-holder embodying my invention is very simple in construction, inexpensive, and, as before stated, will practically prevent the waste of matches or the accidental falling out of the matches.

70 While I have described the device as a holder for matches, it is obvious that it may be used as a holder for toothpicks or the like.

Having thus described my invention, I 75 claim as new and desire to secure by Letters Patent—

A match-holder consisting of a box adapted to receive matches with their original packages, a rear wall of the box being provided 80 with a nail-opening near the top, the said wall also having a downward extension provided with a nail-opening, downwardly-convergent front and rear walls at the lower end of the box, the said inclined rear wall terminating in a forwardly-projecting tray having a trough in its front portion for receiving a single match, the bottom of said tray having an outwardly-opening notch, the said front wall having an opening, and guide members 90 projecting downward at opposite sides of the opening.

In testimony whereof I have signed my name to this specification in the presence of two subscribing witnesses.

MAXAMILIAN JAEGER.
